UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed October 30, 1923. Serial No. 671,631.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

The invention relates to equipment on a typewriting machine for expediting the manipulation therein of work-pieces, such for instance as bill-sheets. Such equipment involves not only a magazine or container from which blank statement or bill sheets 10 may be successively passed to the platen; but also means for facilitating quick placement and fixing of the bills in typing position, and removal thereof from the machine; and preferably means whereby to employ a record-sheet upon which to make the entries, made upon the successive bill-sheets, simultaneously with the typing on the latter. The invention, as to certain features thereof, 15 also relates to feed-roll-releasing means and to means for gaging the position of the work-pieces on the platen. A part of the control means for the feed-rolls is carried by the platen-frame, and other parts of such mechanism are mounted on the carriage, and do not partake of the case-shift movement of the platen-frame relative to the carriage. A control member movably supported on the carriage is operably connected with the feed-rolls on the platen-frame, whereby the case- 20 shift of the platen and its feed-rolls does not disturb the connecting mechanism to change the position of the feed-rolls; and such control member mounted on the carriage imparts substantially the same shift to the feed-rolls in all positions of the platen resulting from its case-feed relative to the carriage.

Heretofore, the magazine or container for the bill-sheets has been out of the body of the machine, in a more or less inconvenient position; or, when in the machine, has been of a kind from which automatic feed of the bill-sheets therefrom, to the platen, has been attempted.

A feature of the present invention is a mounting of the magazine, directly upon the platen-carriage; and whence, regardless of the position of the carriage, the bill-sheets

may be passed by hand, from the magazine, directly down the front of the platen to 55 typing position.

A feature of the invention is a style and setting of magazine, such that the blank work-pieces therein offer themselves separately to the operator's fingers; and such that, upon placement of a pack of work-pieces therein, the latter are caused automatically to step themselves off one from the other so that only one at a time will present itself to the operator's fingers. 65

A feature of the invention is the provision of means, preferably interposing itself in the path of movement of the operator's fingers, whereby, upon insertion of the work-pieces, the same are gaged in correct 70 position for commencement of typing.

A feature of the invention is the provision of means whereby, from the front of the platen, and from any desired position along the platen, the operator may release the feed-rolls; thus obviating the necessity of movement of the operator's hand to the end of the carriage, as heretofore. In this connection, a feature of the invention is a feed-roll-releasing means operable in the sheet-inserting movement of the operator's hand, and by the hand which is inserting the sheet; so that, as the sheet is inserted, the feed-rolls are thrown off the platen to provide free passage around the platen for the sheet 85 so being inserted.

A feature of the invention is a method of using the sheet which has been typed, before removal of the same from the machine, as a means for guiding the next blank sheet 90 into place, down around the platen, from the front thereof, between the platen and the usual paper-apron; and for using such inserted blank sheet as a means for protecting the carbon-sheet from the unremoved 95 typed sheet, so that the latter, upon its removal, will not forwardly displace or crumple the carbon which overlies the record-sheet. In this connection, a feature of the invention is the use of a record-sheet, 100 held by paper-fingers against backward displacement on the platen, as a means for preventing backward displacement (by a statement-sheet on front insertion of the latter) of a carbon-sheet, overlying the record-sheet, 105 not so held by the paper-fingers.

Other features and advantages will hereinafter appear.

In the accompanying drawings,

Figure 1 is a view, in end elevation, partly cross-sectional, of the carriage and associated parts of a typewriting machine embodying the present invention.

Figure 2 is a front view of the apparatus shown in Figure 1.

Figure 3 is a top plan view of the right-hand end of the carriage, showing the feed-roll-releasing means and other parts in association with the platen.

A platen 10, by means of an axle 11, is journaled in the side pieces 12 of the platen-frame. This frame is shiftable up and down between case-positions by any suitable mechanism, not shown. For supporting the platen-frame and assisting in the case-shift of the latter, pins 13 on the side plates of the platen-frame are set upon arms 14 fast to a rock-shaft 15, upon which shaft is a spring, not shown, tending to lift the platen-frame. The case-shifting mechanism 20 may be that shown in the standard Underwood typewriting machine.

The platen-frame is also provided with a paper-shelf 16, which forms an extension of the usual rear paper-table 17 and apron-extension 18, for guiding work-pieces down behind the platen and around under the same to the printing line at the front thereof. The usual front and rear feed-rollers 19 and 20, respectively, are also provided. The front rolls 19 are on a shaft 21, seated on the arms 22 of bell-crank levers pivotally mounted on a shaft 23, secured to the end plates 12 of the platen-frame. The rear feed-rolls 20 are on a shaft 24, seated on the arms 25 of bell-crank levers also pivotally mounted on the shaft 23. The bell-crank levers which comprise the arms 22 have other arms 26 which depend to the rear of a shaft 27; and the bell-crank levers which comprise the arms 25 have other arms 28 which depend to the front of the shaft 27. Leaf-springs 29, bearing upon the arms 22 and 25, tend to rock the arms upward to throw the feed-rolls against the platen, and therefore tend to press the arms 26 and 28 against the shaft 27. The shaft 27 has flats 30 cut therein where the arms 26 and 28 engage the same. When the feed-rolls are in effective position, the arms 26 and 28 bear against the flats 30. When, however, the shaft 27 is rotated, the arms 26 and 28 are forced apart to draw down the feed-rolls. The shaft 27 is journaled in the side plates 12 of the platen-frame. The feed-roll mechanism, just described, is that found in the standard Underwood typewriting machine.

For throwing off the feed-rolls, the following device is employed. Fast to the shaft 27 is an arm 31, which is connected at one end to a link 32; the other end of the

link 32 being connected to a bell-crank lever 33 on a stub-shaft 34, mounted in the right-hand side plate of the platen-frame. One arm 35 of this bell-crank lever connects with a link 36, which extends forward and connects at 37 to one arm 38 of a bell-crank lever fixed to a rock-shaft 39. The rock-shaft 39, at its right-hand end, has bearing in a bracket 40 secured to the right-hand side piece 41 of the carriage. The left-hand end of the rock-shaft 39 is journaled in a bracket 42, which extends forward and is connected to the front rail 43 of the carriage. The bell-crank lever, of which the arm 38 forms a part, also has a forwardly-extending arm 44 which supports the right-hand end of a bar 45. The left-hand end of this bar 45 is supported by an arm 46, also made fast to the rock-shaft 39. Pressure on bar 45, as by the palm, at any point of the bar, results in movement of the bar from the dotted-line Figure 1 position to the full-line Figure 1 position, thereby causing the link 36 to be drawn forward, bell-crank arm 35 to be rocked counterclockwise, and the link 32 to be drawn up to release the feed-rolls. A lip 47, offset from the lower edge of the bar-supporting arm 44, by engagement with the carriage side piece 41, determines the downward movement, and roll-releasing position, of the bar 45.

It will be noted that the link 36, which connects that part of the feed-roll-releasing mechanism which is on the shiftable platen-frame to that part of the feed-roll-releasing mechanism which is on the carriage, is slightly inclined downward and rearward when the shift-frame is in lower-case position. When the shift-frame is in upper-case position, this link 36 is inclined slightly upward and rearward; the true medial position of the link 36 being a horizontal position halfway between its case-positions. By this means, provision is made for the same roll-releasing action of the parts whatever the case-position of the shift-frame. It will be understood that the carriage has movement, in the usual manner, in letter-feed and return directions, on the main frame 48 of the machine. At its rear, the carriage rides upon a rail 49 on the main frame, and, at its front, the carriage is provided with a roll 50, which travels on a runway 51 on the main frame.

In the drawings, a record-sheet 52, faced by a carbon-sheet 53, is shown as having been fed down the table 16 and around the platen, and as having the typed portion thereof extending rearward over the top of the platen. The carbon-sheet is shown as having its leading end turned, at 54, over the leading end of the record-sheet, so that the two sheets may be fed into the machine and around the platen as a unit, without slipping of one on the other. The record-

sheet, as hereinafter explained, is to receive the entries made successively upon a series of individual statements; and, in order that the record-sheet may be held in place upon the platen while the feed-rolls are released for the insertion and removal of the individual statements, a pair of clips are provided. These clips are shown as consisting of spring-fingers 55, carrying rollers 56, which are adapted to bear upon the record-sheet on the platen.

The spring-fingers 55 are secured to U-shaped pieces 57, supported on a shaft 58. The shaft 58, in turn, is supported by similar U-shaped pieces 59, secured to blocks 60 on the side plates 61 of a frame which is set upon and detachably secured to the flanges 62 on the side pieces 12 of the platen-frame. The shaft 58 is revoluble in the brackets 59, but is held against accidental rotation by means of rollers 63 on the brackets 59, which set into a slot 64 extending longitudinally the full length of the shaft 58. Leaf-springs 65 on the brackets 59 hold the rolls 63 in the slot 64, but yield to permit the rolls 63 to cam themselves out of the slot 64, for rotation of the shaft 58 when desired. The U-pieces or brackets 57, which support the paper-clips 55, are held against angular displacement on the shaft 58 by means of rolls 66, similar to the rolls 63, and which are held in the slot 64 by leaf-springs 67, similar to the springs 65. When pressure is applied to the clips 55 to throw the same up to release the record-sheet, the springs 67 yield to permit the rolls 66 to release themselves from the slot 64 in the shaft 58. The detachable frame which supports the shaft 58 is secured to the platen-frame by thumb-screws 68, which pass through the blocks 60 and side pieces 61 of the detachable frame, and which screw into the flanges 62 on the side pieces 12 of the platen-frame.

The shaft 58 also serves as a support for the container or magazine 70 for the blank statement-sheets or bill-heads 71. This container (see Figure 2) has a rear wall 72, a front wall 73, and side walls 74. The front wall 73, toward the base thereof, is tapered downward and rearward, at 75, to the rear wall 72, so that the statement-sheets 71, from rear to front, protrude each slightly above the sheet next rearward of the same; thereby enabling the operator, with his fingers, always to seize one sheet, and not more, at a time.

For supporting the magazine 70 on the shaft 58, there is riveted to the rear wall of the magazine a pair of brackets 76. These brackets, below the lower edge of the magazine, are offset, at 77, rearward for attachment each to a U-shaped bracket 78, similar to the brackets 57 and 59. These brackets 78 are connected to the shaft 58 by rollers 79, set in the slot 64 in the shaft,

and held therein by springs 80, in the same manner as the rollers 63 and 66. Although this form of attachment of the container to the shaft 58 permits angular movement of the container, if desired, the prime purpose of such attachment is to permit the container to be slid rightward or leftward along the shaft to any desired position on the carriage. The rollers 79 and slot 64 obviously make a spline connection of the magazine to the shaft 58; and the pressure of the springs 80 is sufficient to hold the magazine against accidental rightward or leftward displacement. It follows, therefore, that the magazine is placeable and detachable as a unit with the frame which carries the shaft 58 and paper-clips 55; so that, when this detachable frame is not present on the machine, the machine may be used in the ordinary way without unnecessary incumbrances.

In operation, the record-sheet 52 and carbon 53 are fed around the platen to typing position, when the feed-rolls 19 and 20 are in effective position, by means of the usual hand-wheels 81 on the platen-axle 11, or by means of the usual line-space mechanism, of which only a ratchet-wheel 82 on the platen-axle is shown. The paper-finger rollers 56, if not previously applied, are then applied to the record-sheet. The operator then removes the front statement-sheet from the magazine 70 and passes the same down in front of the platen, in front of the carbon-sheet. As the operator's hand moves downward, the operator's palm strikes the bar 45 at some point thereof, and throws off the feed-rolls, permitting the lower edge of the statement-sheet to be passed around the platen between the latter and the apron 18.

The correct position for typing on the first line on the statement-sheet is determined by registration of the upper edge of the statement-sheet with the upper edge of a gage-bar 83. This bar 83 is secured at its ends to arms or brackets 84, in turn, secured to U-shaped pieces or brackets 85, similar to the brackets 59 and 78, and similarly connected to the shaft 58 by means of rollers 86, held by leaf-springs 87 in the slot 64 in the shaft. The left-hand bracket 84 also carries a side-marginal gage for the statement-sheet. This gage is shown as comprising a plate 89, having a flange 90 offset therefrom, against which flange the left-hand margins of the statement-sheets may be set. To permit of adjustment of the marginal gage, the same is slotted, at 91, longitudinally of the plate 89; and screws 92, which secure the gage-plate 89 to the bracket 84, pass through the slot 91. When the screws are tightened, the marginal gage is held in adjusted position.

Upon registration of the upper edge of the statement-sheet with the upper edge of the gage-bar 83, the operator's hand is lifted

to release the bar 45 and to permit the springs 29 to throw the pressure-rolls to position for holding the statement-sheet. If typing at the first position on the statement-sheet is not desired, and typing is desired at some other position on the statement-sheet, the usual wing-scales, not shown, may be used, instead of the gage-bar 83, as the means for gaging the position of the statement-sheet. The statement-sheet may be held up against the platen, above the printing line, by means of the usual movable paper-holding finger or guard, which is not shown, but which is pivotally connected to the front rail of the carriage, and is found in standard Underwood typewriting machines.

After typing on a statement-sheet is completed, the carriage is thrown rightward for commencement of writing on another statement-sheet. The lever by which the carriage is thus returned, ordinarily effects a single line-space movement of the platen by mechanism not here shown. This results in a line-space movement of the record-sheet 52 and carbon 53 so as to prepare the same for receiving the entries to be made upon the next succeeding statement-sheet. The paper finger or guard, last mentioned, is thereupon thrown out, and the statement-sheet, which has been typed, pulled forward as indicated in Figure 1. Thereupon, the operator removes from the magazine 70 the front statement-sheet therein, and passes the same down between the platen and the statement-sheet last typed. In so doing, the operator's hand depresses the bar 45 to release the feed-rolls, so that the statement-sheet, then being introduced, may be passed around the platen between the feed-rolls and the platen. In this operation, the previously-typed statement-sheet serves to guide the next statement-sheet around the platen between the front edge of the apron 18 and the platen. While the newly-inserted statement-sheet is held with its upper edge aligned with the upper edge of the gage-bar 83, the operator, with his other hand, then removes the previously-typed statement-sheet. This done, the operator removes his hand from the bar 45 and from the newly-inserted statement-sheet. All is now ready for typing on the statement-sheet then in the machine.

It will be noted upon reference to Figure 2 that the paper-finger rolls 55 do not bear upon the carbon-sheet; they bear upon the record-sheet outside of the side boundaries of the carbon-sheet. For holding the carbon-sheet against forward displacement or crumpling during the removal of a typed statement, paper-fingers are not necessary in the present case; because, as hereinbefore stated, the fresh statement-sheet is inserted between the platen and the typed statement-

sheet before the latter is removed. The fresh statement-sheet, therefore, prevents frictional engagement of the typed statement-sheet with the carbon-sheet as the typed statement-sheet is pulled out. On removal of the typed statement-sheet, the same therefore slides over the outer face of the inserted fresh statement-sheet, without dragging on the carbon. The carbon-sheet is also held against backward displacement around the platen, without direct application of any paper-fingers thereto. This is because the paper-finger rolls bear upon the record-sheet to hold the latter against backward displacement; and the leading end of the carbon-sheet being looped over the leading end of the record-sheet, the record-sheet holds the carbon-sheet against backward displacement. The statement-sheet upon being inserted, therefore, instead of disturbing the carbon-sheet, only tends to smooth the same out on the platen.

Variations may be resorted to within the scope of the invention, and portions of the improvements may be used without others.

Having thus described my invention, I claim:

1. In a typewriting machine, a platen, a platen-frame, a carriage for the platen-frame having side pieces and a front cross-piece, feed-rolls to co-operate with the platen, and means to release the feed-rolls, comprising a bar extending lengthwise of the carriage, arms for supporting the bar, a shaft for pivotally supporting the arms, and bearing pieces for the shaft, one on one of the carriage side pieces and one on the carriage front piece.

2. In a typewriting machine, a platen, a platen-carriage, a frame for the platen set upon the platen-carriage, means for shifting the platen-frame between case-positions on the carriage, feed-rolls to co-operate with the platen, means for releasing the feed-rolls, comprising a bar on the carriage extending lengthwise of the carriage, a lever on the platen-frame, and a link connecting the bar on the carriage with the lever on the platen-frame.

3. In a typewriting machine, a platen, a platen-carriage, a frame for the platen set upon the platen-carriage, means for shifting the platen-frame between case-positions on the carriage, feed-rolls to co-operate with the platen, means for releasing the feed-rolls, comprising a bar on the carriage extending lengthwise of the carriage, a bell-crank lever supporting the bar on the carriage, a lever on the platen-frame, and a link connecting the bell-crank on the carriage with the lever on the platen-frame.

4. In a typewriting machine, a platen, a platen-carriage, a frame for the platen set upon the platen-carriage, means for shifting the platen-frame between case-positions on

- the carriage, feed-rolls to co-operate with the platen, means for releasing the feed-rolls, comprising a bar on the carriage extending lengthwise of the carriage, a lever 5 on the carriage connected to the bar, a lever on the shiftable platen-frame, and a link extending substantially horizontally rearward and connecting the lever on the carriage with the lever on the platen-frame.
- 10 5. In a typewriting machine, a platen, a platen-carriage, a frame for the platen set upon the platen-carriage, means for shifting the platen-frame between case-positions on the carriage, feed-rolls to co-operate with the platen, means for releasing the feed-rolls, comprising a bar on the carriage extending lengthwise of the carriage, a lever on the carriage connected to the bar, a lever on the shiftable platen-frame, and a link extending 15 substantially horizontally rearward and connecting the lever on the carriage with the lever on the platen-frame, said link, in the lower-case-setting of the platen-frame, being inclined rearward and slightly downward, and, in the upper-case-position of the platen-frame, being inclined rearward and slightly upward.
6. In a typewriting machine, a platen, a platen-carriage, a frame for the platen set 20 upon the platen-carriage, means for shifting the platen-frame between case-positions on the carriage, feed-rolls to co-operate with the platen, means for releasing the feed-rolls, comprising a bar on the carriage extending 25 lengthwise of the carriage, a lever on the carriage connected to the bar, a lever on the shiftable platen-frame, and a link extending substantially horizontally rearward and connecting the lever on the carriage with the lever on the platen-frame, said link, in the lower-case-setting of the platen-frame, being inclined rearward and slightly downward, and, in the upper-case-position of the platen-frame, being inclined rearward and 30 slightly upward, the horizontal position of the link being midway between upper and lower case-positions, so as to effect the same feed-roll-releasing movement in both case-positions.
- 35 7. In a typewriting machine, a platen, a carriage for the platen, a gage on the carriage, comprising a bar extending lengthwise thereof above the platen, for positioning work-sheets by their upper edges with respect to the platen, feed-rolls to co-operate with the platen, and feed-roll-releasing means comprising a bar on the carriage, extending lengthwise of the carriage, in position to be actuated by the hand of the operator, while the operator with the same hand gages the work-sheets.
- 40 8. In a typewriting machine, a platen, a platen-frame, a carriage, a magazine for work-sheets disposed above the platen, a gage for positioning the work-sheets, by 45
- their upper edges, relatively to the platen, on front insertion of the same, mounted upon the carriage, a feed-roll for the platen, and a feed-roll-release bar supported on the carriage below said gage in position to be 50 reached by the operator's hand while adjusting a work-sheet to said gage by the same hand.
9. In a typewriter having a carriage and a frame carrying a revoluble platen, which frame is shiftable for case-position feed of the carriage, feed-rolls on the platen-frame normally pressed against the platen, and means for shifting the feed-rolls including mechanism having a control member mounted on the carriage and which control member will effect substantially the same shifting movement of the rolls in all positions of the platen caused by its case feed. 55
10. In a typewriter having a carriage and a frame carrying a revoluble platen, which frame is shiftable for case-position feed of the carriage, feed-rolls on the platen-frame normally pressed against the platen, and means for shifting the feed-rolls comprising 60 a lever having a pivot fast on the platen-frame, means for shifting the feed-rolls from said lever, a control lever pivoted on the carriage, and a link connecting said two levers, which said parts are relatively 65 arranged whereby swinging the control lever will cause a thrust movement of the link and rock said other lever to shift the feed-rolls in all of the case-feed positions of the platen. 70
11. In a typewriter having a carriage and a frame carrying a revoluble platen, which frame is shiftable for case-position feed of the carriage, feed-rolls on the platen-frame normally pressed against the platen, and means for shifting the feed-rolls comprising 75 a lever having a pivot fast on the platen-frame, means for shifting the feed-rolls from said lever, a control lever pivoted on the carriage, and a link connecting said two levers, which said parts are relatively 80 arranged whereby swinging the control lever will cause a thrust movement of the link and rock said other lever to shift the feed-rolls in all of the case-feed positions of the platen, while said case-feed shifts of the platen-frame and its said lever will rock the link without producing end thrust or shift of the feed-rolls. 85
12. In a typewriter having a carriage and a frame carrying a revoluble platen, which frame is shiftable for case-position feed of the carriage, feed-rolls on the platen-frame normally pressed against the platen, and means for shifting the feed-rolls including mechanism having a control member mounted on the carriage and which control member will effect substantially the same shifting movement of the rolls in all positions of the platen caused by its case-feed, and a bar on said control lever extending parallel 90

with the platen to shift the feed-rolls on depression of said bar at any point throughout its length.

13. In a typewriter having a carriage and
5 a frame carrying a revoluble platen, which
frame is shiftable for case-position feed of
the carriage, feed-rolls on the platen-frame
normally pressed against the platen, and
means for shifting the feed-rolls including
10 mechanism having a control member mounted
on the carriage and which control member
will effect substantially the same shifting
movement of the rolls in all positions of

the platen caused by its case-feed, and a bar
on said control lever extending parallel with
the platen to shift the feed-rolls on depression
of said bar at any point throughout the
length of the bar, said bar being placed a
considerable distance in front of the platen
for engagement by the palm of the operator
at the same time that the fingers manipulate
the work-sheet adjacent the platen,
while the hand causes the bar to retain the
feed-rolls in free position to admit the work-
sheet. 15 20

JESSE A. B. SMITH.
